UNITED STATES PATENT OFFICE

LOTHAR A. EDERER, OF CHICAGO, ILLINOIS, ASSIGNOR TO R. J. EDERER CO., OF CHICAGO, ILLINOIS, A CORPORATION OF ILLINOIS

NET PILER

Application filed March 8, 1930. Serial No. 434,434.

This invention relates to a machine for handling, conveying and piling material. In the embodiment illustrated herewith the machine is a piling machine. The invention is, of course, not limited to this use and the machine might be used as a conveyor whether or not it actually embodies means for piling and whether or not it is used for that purpose, no matter what means it may include.

The invention has for one object to provide a machine which may be used in conveying fabrics, and in the form illustrated it is particularly applicable to the handling, conveying and piling of nets and netted fabrics.

It has for one object to provide a machine which may be used in the conveying and piling of nets and which will automatically engage the net and automatically disengage itself from the net.

Another object is to provide a machine which will handle a fabric and which will move it, engage it and pile it and distribute it evenly. Another object is to provide in connection with a fabric handling machine means for distributing the material as it leaves the machine, both longitudinally and transversely of the machine. This latter object is of particular importance when the machine is used to pile material.

Other objects will appear from time to time in the specification and claims:

My invention is illustrated more or less diagrammatically in the accompanying drawings, wherein:

Figure 1 is a side elevation of one form of the machine;

Figure 2 is a vertical cross section taken on line 2-2 of Figure 1, looking in the direction of the arrow in Figure 1;

Figure 3 is a partial transverse cross section taken on an enlarged scale on line 3-3 of Figure 2, showing the fabric engaging parts and their moving mechanisms;

Figure 4 is a vertical cross section with some parts in elevation and with parts broken away, taken at line 4-4 of Figure 3 and showing on an enlarged scale a portion

of the driving mechanism for the material engaging elements;

Figure 5 is a plan view of one of the engaging elements, as shown in Figure 4;

Figure 6 is a side elevation of a modified form in which a single material engaging beater or roll is used;

Figure 7 is an end view of the machine of Figure 6, with parts broken away and parts in section;

Figure 8 is an elevation of a modified form of distributing conveyor;

Figure 9 is a view generally similar to Figure 8, showing a modified driving mechanism for the guiding ring.

Like parts are designated by like characters throughout the specification and drawings.

The machine may be supported or suspended from any suitable foundation or other support. As shown it is supported from a ceiling or overhead supporting member A. The several forms of the invention illustrated are all shown as supported thus from above. A may be a roof and it may join a wall or generally vertical member A¹. In the form of the invention illustrated in Figures 1 to 5, inclusive, a frame member A² is supported from the member A. Downwardly depending frame members A³ A⁴ engage the member A² and engage and support a bottom frame member A⁴ which has upwardly extending portions A⁵ which are joined as at A⁶ by any suitable means to the frame member A².

Supported by the frame made up of the members just described is a machine frame which carries the parts of the machine to be described below. The frame has two side assemblies and each of these may be made integrally. Each of these assemblies includes an upper longitudinal member B, a lower longitudinal member B¹, which may be longer than the upper member, one or more vertical members B² joining the members B and B¹ and inclined end members B³ B⁴ which further join the top and bottom members. The main rotating parts of the machine are mounted between the two side assemblies.

C is an extension from one side of the frame

assembly and it may carry a motor C¹ which has a shaft C² carrying a driving pinion C³.

In the form of the invention illustrated in the first five figures, two rotors are used and these carry the paddles or arms which in turn carry and support the fabric engaging members. A description of one of these will suffice since they are normally identical with each other. For each of the rotors two cam members D are preferably provided. These members are fixed with relation to the rotor and may be supported on the side frame assemblies made up of the parts B, B¹, B² and B³. It is sufficient that they be fixed with relation to the rotor. Each of the cam members D has a cam groove D¹ formed in it. This may be formed in any suitable manner, either by being formed integrally with the member D or by the use of additional parts D² properly shaped and attached to the member D.

The cam groove D¹ is shaped so as to have at its lower portion, which is generally designated by the letter X, a longer radius than it has at its upper portion, generally designated by the letter Y.

Supported from and in some cases forming a part of the upper members B of the side frame assemblies, are bearing supporting parts E, E. Two pairs of these are provided. Within each pair of the members E is supported a shaft E¹ which extends laterally across the machine and carries one of the rotors. Two hub portions E² are mounted on each shaft at opposed ends thereof, and each of the hub portions carries a plurality of extending channel arms E³. Positioned between each pair of arms E³ and extending from the shaft E¹ to a point adjacent the outer end of the arms E³ and engaged by their channels, is a web E⁴. Each of the arms E³ supports a bearing or slide block E⁵, within which is slidably positioned a rod E⁶. The rod E⁶ may carry at its inner end a lateral extension E⁷ upon which is rotatably mounted a cam roller E⁸, which lies within the cam groove D¹, which is itself defined and bounded by the members D² D². Extending laterally across the machine and between each pair of rods E⁶ is a shield member E⁹. This member, as shown, is made up of a plurality of parts so shaped and arranged as to provide slots or openings E¹⁰. Each of the web members E⁴ is shaped on its outer edge as at E¹¹ to provide notches or otherwise shaped engaging parts to engage the fabric upon which the machine is operating. Each of the webs E⁴ also carries additional fabric engaging members E¹² E¹² which may be made as shown of angles having their exposed edges shaped like the portion E¹¹ of the web E⁴. These angles are joined to the web by suitable attaching parts E¹³. E¹⁴ E¹⁴ are angle members generally similar to the members E¹³.

They engage the members E¹² and at their ends are also attached to the arms E³ and assist in holding the webs E⁴ in position. The shape of the cam groove is such that as the rotors move and as each arm is brought toward the downward position, as shown for example in the lowest arm in Figure 3, the member E⁹ is moved outwardly so as to cover the edges E¹¹ E¹² and thus to prevent their engagement or free them from engagement with any material which may be in contact with them. As the arms move into the upper position, such for example as shown in the three upper arms of Figure 3, the member E⁹ is moved inwardly by the cam groove and so uncovers the edges E¹¹ and E¹² and thus frees them so that they may engage any material which is in contact with them.

Supported in suitable bearings in the framework is a shaft F on which is positioned a gear F¹ with which the pinion C³ is in mesh. Mounted on the same shaft F so as to be driven by it is a pinion F² which meshes with a gear F³ on the shaft E¹. Thus the rotation of the motor C drives the shaft E¹ and thus drives the rotor which has been described above.

A second rotor which is identical in construction with the rotor above described is carried on a shaft G which is supported in the bearing supports E as above mentioned. The shaft E¹ which carries the gear F³ has at its opposite end a gear F⁴. At the same end the shaft G carries a gear G¹. G² and G³ are gears suitably supported in bearings, the gear G² meshing with the gear F⁴ and the gear G³ meshing with the gear G² and the gear G⁴. Thus rotation of the shaft E² of the left hand rotor, as shown in Figure 1, drives the shaft of the right hand rotor as shown in that figure, through the gears F⁴, G¹, G² and G³.

H is a shaft which may be supported in the lower members B¹ of the side frame assemblies. It has fixed to it members H¹ provided with extensions H² which are fastened to frame members H³ which may be of angular cross section as shown, and which have attached to them one or more boards or plates H⁴. These boards, together with the members H³, make up a swinging guiding member. H⁵ is one part of a clutch. H⁶ is a mating clutch part. H⁷ is a spring tending normally to hold the clutch members out of engagement and the member H⁶ has an upward extension H⁸ to which a lever arm H⁹ is fastened. This arm may be provided with a slot H¹⁰ in which one end of a connecting rod H¹¹ may be adjustably positioned. At its other end the connecting rod has an adjustably mounted bearing block H¹² to which a crank arm H¹³, which is fixed with relation to the shaft G is attached. By means of this mechanism when the clutch is in engagement rotation of the shaft G rotates

the crank H^{13} and thus gives a swinging motion to the guiding members H^3 H^4 . H^{14} is a clutch operating part which has operating handles H^{16} H^{15} by means of which the clutch 5 may be operated and controlled so as to engage and disengage the clutch parts to throw the guiding member into movement or to disengage the drive mechanism to stop its movement.

10 I I are supports which are fastened to the frame member A^4 A^5 . There are four of the members I and between each pair extends a shaft I^1 which may be fixed against movement by means of set screws I^2 I^2 . Each of 15 the shafts I^1 is broken at its center and a guiding ring I^3 is inserted. Rotation of the shaft accordingly rotates the ring. As shown the shaft is of sufficient length to permit it to be moved laterally so as to move the 20 ring laterally across the entire width of the machine. The shaft may also be rotated so as to vary the angular position of the ring. No mechanism has been shown for moving the shaft as it can be done manually or by any 25 suitable mechanism.

J indicates the material which is being moved through the machine. It is moved in the direction of the arrows, passing through the guide ring I^3 around the left hand rotor, 30 it is engaged by this rotor and by the second or right hand rotor, and passes down and is contacted and moved by the guiding plate. The reason for a second guiding ring I^3 is that the machine can take material from 35 either side. If it were feeding from the right hand instead of from the left hand, as shown in Figure 1, the material at first passes through the right hand guide ring I^3 and then over the right hand rotor and from there 40 on in the same line as shown.

In Figures 6, 7 and 8, a modified construction is shown. It is generally similar to that shown in the earlier figures and differs from that form mainly by the fact that only a 45 single rotor is provided. This rotor operates generally in the same manner as those already described but is simpler in construction. Supported from the ceiling or other support A and preferably extending downwardly from it, is a pair of arms K. Journaled adjacent the lower end of these arms is a shaft K^1 which carries at one end a gear K^2 . At its opposite end it has fixed to it a pinion K^3 which is in mesh with a gear K^4 .

55 L L are supporting plates which may be fastened to the members K or may be held rigid in any other suitable manner. Each of them is provided with members L^1 L^1 which, together, form cam grooves L^2 L^2 . The 60 plates L are provided with extensions L^3 . They are further provided with extensions L^4 . The right hand plate L, as shown in Figure 6, has formed on it a boss L^5 within which a short shaft is journaled which carries the pinion K^5 above mentioned. The left hand

plate L, as shown in Figure 6, is provided with a relatively short boss L^6 and the right hand plate, as shown in the same figure, is provided with a similarly placed but preferably somewhat larger boss L^7 .

70 Journalized in the bosses L^6 and L^7 is a shaft M. A guiding plate M^1 is supported from the shaft M by means of one or more hinge members M^2 which are fixed with relation to the shaft so as to swing with it. A baffle M^3 is formed as a part of the guiding plate M^1 and is supported from it by means of supports M^4 , the baffle M^3 being somewhat separated from the plate M^1 so that a space M^5 is provided between the two along their adjacent edges. Fixed on the shaft M is a bell crank M^6 to which a connecting rod M^7 is pivoted at one end. At its other end the member M^7 is pivoted to the pinion K^4 so that rotation of that pinion gives a swinging motion 75 to the member M^6 and correspondingly to the guiding plate M^1 .

80 Fixed in the extensions L^4 of the plates L is a pair of guide shafts N. Mounted to slide on these guides N is a guiding ring N^1 which is provided with a perforation N^2 . At one end the ring N^1 is attached to an operating rod N^3 which is provided with a bent end N^4 . N^5 is an operating handle pivotally supported 85 on a member N^6 which is itself fixed on the wall member A¹. The handle is mounted to swing and is provided with a slot N^7 through which the bent end N^4 of the rod N^3 extends. The handle N^5 may be swung and so moves 90 the member N^3 and the ring N^1 longitudinally across the machine. N^8 is a stop which may be provided to limit the movement of the ring in one direction. As shown in Figure 95 6, this stop is positioned in the right hand plate L.

100 O is a driving motor which as shown is mounted on the ceiling A. O¹ is a motor shaft which carries a pinion O² which is in mesh with the gear K² on the shaft K¹.

110 The rotor is generally similar to that shown and described in connection with Figures 1 to 5 inclusive. K¹ is the shaft of the rotor. It is rotated by the means described above. It is provided with hubs P from which arms P¹ extend. Fitted into grooves in the shaft K¹ and into grooves in the arms P¹ are webs P² which have their outer edges notched or roughened as at P³. It will be noticed that for each web there is but a single such roughened or notched edge instead of the three roughened edges for each web as shown in Figures 1 to 5. For each web P² a double guard is provided. This guard is formed of two members as shown. They are preferably 115 spread apart from each other slightly at each end, as indicated in Figure 6, and a block P⁵ is inserted at this point and the two members of the guard P⁴ are fastened to this block. Supported in each of the blocks P⁵ is a roller P⁶ which extends into the cam groove L². 120

Thus as the shaft is rotated the guards move out so as to mask the notched edges P^3 when they are in the lower portion of their rotation, and they are moved back so as to unmask them and to free them from engagement with material when they are in the upper part of their rotation.

Q is a bar which may be supported from the ceiling A and bent so as to form a guide or 10 loop through which the material Q¹ is first fed. Thereafter the material is fed through the guiding ring N¹ about the rotor, down along the upper surface of the guiding plate M¹ and through the opening M².

15 In Figure 8 a detail of a modified driving mechanism for the guiding ring is shown. The assembly is supported on the extensions L⁴ of the plates L in the manner shown in Figure 6 and 7. Similar guide rods N N are used. A guiding ring R is used. It is provided with a perforation R¹ and is shaped to engage or slide along the rods N. It is provided with a nut R² and a double threaded rotary shaft R³ passes through and is engaged by the nut R². This shaft is supported in suitable bearings in the extensions L⁴ and is provided at its outer end with a sprocket R⁴. A second sprocket R⁵ is mounted on a shaft R⁶ which is supported for rotation from any 20 suitable support, such as that indicated diagrammatically at R⁷. A chain R⁸ meshes with the sprockets R⁴ and R⁵. A hand wheel R⁹ is provided for rotating the shaft R⁶ and a handle R¹⁰ is provided for rotating the 25 wheel R⁹.

In Figure 9 the driving means for moving the guiding ring R is essentially the same as that shown in Figure 8, but is driven automatically from the machine itself. S is a 40 sprocket driven by the machine. S¹ is a chain engaging the sprocket R⁴ and the sprocket S, and thus when the machine is driven the sprocket S is driven and through the chain S¹ and the sprocket R⁴ the threaded shaft R³ is rotated and the guide ring R is caused to move constantly to and fro across the machine. While no clutch has been shown, it is understood that a clutch might be used so that the driving mechanism for 45 the driving ring could be disconnected and the drive ring might thus, when disconnected, be moved slightly by hand or left stationary during the operation of the machine. It will be understood that the driving mechanism 50 guiding ring, as shown in Figure 9, might be inserted into the form of the invention shown either in the first five figures or in Figures 6 and 7. When so inserted the machine would provide automatic guiding movement 55 of the ring and of the swinging guiding plate so that material fed to the machine is guided automatically to and fro across the machine along a line generally parallel to its axis of rotation. This is accomplished, of course, 60 by means of the guiding ring. At the same

time, and automatically by means of the swinging guiding plate, the material as it is discharged from the machine is guided to and fro. Thus, if it is being fed onto a pile, for example, it is fed on the pile in layers 70 which are folded back and forth.

It will be understood that while I have shown and described a practical operative device, many changes might be made in the size, shape, number and disposition of parts without departing materially from the spirit of my invention and I wish therefore that my showing be taken as in a sense diagrammatic.

The use and operation of the machine as shown in the several figures are generally 80 similar. While it might be used to handle, convey and pile many sorts of material, I shall describe it in connection with the handling and piling of net, although it is, of course, not limited in its use to this material. If net is to be piled, a portion of it will be inserted through the guide ring and will then be moved over the rotor adjacent to the guide ring, whether there is more than one rotor used or not. Since the arrangement 85 of the cams is such that the engaging edges of the rotor are uncovered and in position for engagement when they are generally in the upper part of the rotor, the portion of the net which is put upon the top of the rotor 90 will be at once engaged by the exposed edges. The machine may be started and if there be two rotors, they rotate toward each other, the net being fed and conveyed down between them and being engaged by both of 95 them.

As the several arms of the rotors move from the upper to the lower position their engaging edges are gradually covered so that as they approach their lower positions they are totally masked and they can no longer engage the net, which is thus free to pass below the machine as indicated in Figure 1 in particular, and also in Figure 7. If the swinging guiding plate is in operation it will contact the net and guide it first to the right 105 as indicated in Figure 1, and then to the left. Thus the strip of net, as it leaves the machine, is swung back and forth so as to be piled in layers or if it is to be piled in a container, it is more evenly arranged throughout the 110 container as a result of being thus swung back and forth. These two guiding operations may be accomplished manually or automatically. They may be accomplished simultaneously or either may be omitted or 115 for some purposes both may be omitted and then the material is simply engaged by one or more rotor and is pulled through the machine and is discharged from it.

I claim:

1. In a material moving assembly, a member provided with a material engaging part, a mask for said part, means for moving said mask to mask said part and to unmask it, whereby it is permitted to engage and dis-

- engage material, and a moving means for said mask, adapted to mask and to unmask the engaging means at suitable points in the cycle of operation.
5. 2. In a material moving assembly, a member provided with a material engaging part, a mask for said part, means for moving said mask to mask said part and to unmask it, whereby it is permitted to engage and disengage material, and a moving means for said mask, adapted to mask and to unmask the engaging means at suitable points in the cycle of operation.
10. 3. In a material moving assembly, a rotary member provided with a material engaging part, a mask for said part, means for moving said mask to mask said part and to unmask it, whereby it is permitted to engage and disengage material, and a moving means for said mask, adapted to mask and to unmask the engaging means at suitable points in the cycle of operation.
15. 4. In a material moving assembly, a rotary member provided with a material engaging part, a mask for said part, means for moving said mask to mask said part and to unmask it, whereby it is permitted to engage and disengage material, and an automatic moving means for said mask, adapted to mask and to unmask the engaging means at suitable points in the cycle of operation.
20. 5. In a material moving assembly, a rotary member provided with a material engaging part, a mask for said part, means for moving said mask to mask said part and to unmask it, whereby it is permitted to engage and disengage material, and an automatic moving and controlling means for said mask, adapted to mask and to unmask the engaging means at suitable points in the cycle of operation.
25. 6. In a material handling apparatus, a plurality of bodily movable material guiding means associated with said apparatus, and movably mounted driving means therefor and driving connections whereby said guiding means are moved, the paths of movement of the two guiding means being angularly disposed with respect to each other.
30. 7. In a material handling apparatus, a plurality of bodily movable material guiding means associated with said apparatus, and movably mounted driving means therefor and driving connections whereby said guiding means are moved, the paths of movement of the two guiding means being angularly disposed with respect to each other, one moving longitudinally with respect to the machine and the other transversely with respect thereto.
35. 8. In a material handling apparatus, a plurality of bodily movable material guiding means associated with said apparatus, and movably mounted driving means therefor and driving connections whereby said guiding means are moved, the paths of movement of the two guiding means being angularly disposed with respect to each other, one moving longitudinally with respect to the machine and the other transversely with respect thereto.
40. 9. In a material handling apparatus, a material moving mechanism, a plurality of bodily movable material guiding means associated with said apparatus, and movably mounted driving means therefor and driving connections whereby said guiding means are moved, one of said guiding means engaging and guiding material on its way to the moving mechanism.
45. 10. In a material handling apparatus, a material moving mechanism, a plurality of material guiding means associated with said apparatus, and movably mounted driving means therefor and driving connections whereby said guiding means are moved, one of said guiding means engaging and guiding material on its way to the moving mechanism, the other engaging and guiding it after it leaves the machine.
50. 11. In a material handling apparatus, a material moving mechanism, a plurality of material guiding means associated with said apparatus, and movably mounted driving means therefor and driving connections whereby said guiding means are moved, one of said guiding means engaging and guiding material on its way to the moving mechanism, the paths of movement of the two guiding means being angularly disposed with respect to each other, one moving longitudinally with respect to the machine and the other transversely with respect thereto.
55. 12. In a material handling apparatus, a material moving mechanism, a plurality of material guiding means associated with said apparatus, and movably mounted driving means therefor and driving connections whereby said guiding means are moved, one of said guiding means engaging and guiding material on its way to the moving mechanism, the other engaging and guiding it after it leaves the machine, the paths of movement of the two guiding means being angularly disposed with respect to each other, one moving longitudinally with respect to the machine and the other transversely with respect thereto.
60. 13. In a material handling apparatus, a material moving mechanism, a plurality of material guiding means associated with said apparatus, and movably mounted driving means therefor and driving connections whereby said guiding means are automatically moved, one of said guiding means engaging and guiding material on its way to the moving mechanism, the other engaging and guiding it after it leaves the machine, the paths of movement of the two guiding means being angularly disposed with respect to each other, one moving longitudinally with respect to the machine and the other transversely with respect thereto.
65. 14. In combination in a fabric handling machine, a fabric moving member, fabric engaging parts on said member, means for masking and unmasking them to prevent and

permit engagement with a fabric, a fabric guiding member mounted for movement and means for moving it.

15. In combination in a fabric handling machine, a fabric moving member, fabric engaging parts on said member, means for masking and unmasking them to prevent and permit engagement with a fabric, a fabric guiding member mounted for movement and automatic means for moving it.

16. In combination in a fabric handling machine, a fabric moving member, fabric engaging parts on said member, means for masking and unmasking them to prevent and permit engagement with a fabric, a plurality of fabric guiding members mounted for movement and means for moving them.

17. In combination in a fabric handling machine, a fabric moving member, fabric engaging parts on said member, means for masking and unmasking them to prevent and permit engagement with a fabric, a plurality of fabric guiding members mounted for movement and automatic means for moving them.

18. In combination in a fabric handling machine, a fabric moving member, fabric engaging parts on said member, means for masking and unmasking them to prevent and permit engagement with a fabric, a plurality of fabric guiding members mounted for movement and means for moving them, one of said guiding members mounted for movement in axial alignment with said fabric moving member and the other of said guiding members mounted for movement transversely with respect to the axis of said fabric moving member.

19. In combination in a fabric handling machine, a fabric moving member, fabric engaging parts on said member, means for masking and unmasking them to prevent and permit engagement with a fabric, a plurality of fabric guiding members mounted for movement and automatic means for moving them, one of said guiding members mounted for movement in axial alignment with said fabric moving member and the other of said guiding members mounted for movement transversely with respect to the axis of said fabric moving member.

20. In combination in a fabric handling machine, a fabric moving member mounted for rotation, fabric engaging parts on said member, means for masking and unmasking them to prevent and permit engagement with a fabric, a plurality of fabric guiding members, mounted for movement and automatic means for moving them, one of said guiding members mounted for movement in axial alignment with said fabric moving member and the other of said guiding members mounted for movement transversely with respect to the axis of said fabric moving member.

21. In a net handling machine, a plurality of net engaging members, means for driving them, whereby they both engage the net, and two net guiding means adapted to engage the net, driving means for said guiding members whereby they are moved to guide the net, the net engaging members including a plurality of net engaging teeth, movable masking members for said teeth, automatic means for moving said masking members to mask said teeth and for moving said masking members to unmask said teeth.

22. In a net handling machine, a plurality of net engaging members, means for driving them, whereby they both engage the net, and two net guiding means adapted to engage the net, driving means for said guiding members whereby they are moved to guide the net, the net engaging members including a plurality of net engaging teeth, movable masking members for said teeth, automatic means for moving said masking members to mask said teeth and for moving said masking members to unmask said teeth, whereby the net engaging teeth are freed to engage the net at a suitable point in their cycle of movement and are covered to disengage them from the net at a suitable point in their cycle of movement.

23. In a net handling machine, a plurality of net engaging members, means for driving them, whereby they both engage the net, and two net guiding means adapted to engage the net, driving means for said guiding members whereby they are moved to guide the net, and means for controlling the net engaging members, whereby material is engaged by them and disengaged from them at suitable points in the cycle of movement of the machine.

24. In a net handling machine, a plurality of net engaging members, means for driving them toward each other, whereby they both engage the net, and two net guiding means adapted to engage the net, driving means for said guiding members whereby they are moved to guide the net.

25. In a net handling machine, a plurality of net engaging members, means for driving them, whereby they both engage the net, and two net guiding means adapted to engage the net, one as it enters the machine, the other as it leaves the machine, automatic driving means for said guiding members whereby they are moved to guide the net.

26. In a net handling machine, a plurality of net engaging members, means for driving them, whereby they both engage the net, and two net guiding means adapted to engage the net, one as it enters the machine, the other as it leaves the machine, automatic driving means for said guiding members whereby they are moved to guide the net, one of said

guiding means adapted to guide the net longitudinally across the machine.

27. In a net handling machine, a plurality of net engaging members, means for driving them, whereby they both engage the net, and two net guiding means adapted to engage the net, one as it enters the machine, the other as it leaves the machine, automatic driving means for said guiding members whereby they are moved to guide the net, one of said guiding means adapted to guide the net longitudinally across the machine, the other adapted to guide the net transversely with respect to the machine.

28. In a net handling machine, a plurality of net engaging rotary members, means for driving them toward each other, whereby they both engage the net, and two net guiding means adapted to engage the net, one as it enters the machine, the other as it leaves the machine, automatic driving means for said guiding members whereby they are moved to guide the net, one of said guiding means adapted to guide the net longitudinally across the machine, the other adapted to guide the net transversely with respect to the machine, and means for throwing said guiding means into and out of operation.

29. In a net handling machine, a plurality of net engaging rotary members, means for driving them toward each other, whereby they both engage the net, and two net guiding means adapted to engage the net, one as it enters the machine, the other as it leaves the machine, automatic driving means for said guiding members whereby they are moved to guide the net, one of said guiding means adapted to guide the net longitudinally across the machine, the other adapted to guide the net transversely with respect to the machine, and means for throwing said guiding means into and out of operation, the net engaging members including a plurality of net engaging teeth, movable masking members for said teeth, automatic means, including cams, for moving said masking members to mask said teeth and for moving said masking members to unmask said teeth, whereby the net engaging teeth are freed to engage the net at a suitable point in their cycle of movement and are covered to disengage them from the net at a suitable point in their cycle of movement.

30. A material moving apparatus, including a rotor and a material engaging part, means for covering said material engaging part and automatic means whereby said covering means is moved to cover and uncover said engaging part at suitable points in the cycle of rotation of the material moving apparatus, said covering part including a shield.

31. A material moving apparatus, including a rotor and a material engaging part, means for covering said material engaging part and automatic means whereby said cov-

ering means is moved to cover and uncover said engaging part at suitable points in the cycle of rotation of the material moving apparatus, said covering part including a shield, the operating means therefor including a cam, cam rollers engaging in said cam and connected to said shield.

32. A material moving apparatus, including a rotor and a material engaging part, means for covering said material engaging part and automatic means whereby said covering means is moved to cover and uncover said engaging part at suitable points in the cycle of rotation of the material moving apparatus, said covering part including a shield, the operating means therefor including a cam fixed with relation to the rotor, cam rollers engaging in said cam and connected to said shield.

33. A material moving apparatus, including a rotor having arms and a material engaging part on said arms, means for covering said material engaging part and automatic means whereby said covering means is moved to cover and uncover said engaging part at suitable points in the cycle of rotation of the material moving apparatus, said covering part including a shield.

34. A material moving apparatus, including a rotor having arms and a material engaging part on said arms, means for covering said material engaging part and automatic means whereby said covering means is moved to cover and uncover said engaging part at suitable points in the cycle of rotation of the material moving apparatus, said covering part including a shield, the operating means therefor including a cam fixed with relation to the rotor, cam rollers engaging in said cam and connected to said shield.

Signed at Chicago, county of Cook and State of Illinois, this 4th day of March, 1930.

LOTHAR A. EDERER.
